STEAM GENERATOR HEATING UNIT

Filed April 18, 1928

FIG. 1.

FIG. 4.

FIG. 5.

FIG. 7.

INVENTOR,
John B. Odell,
BY
F. E. Maynard,
ATTORNEY.

UNITED STATES PATENT OFFICE.

JOHN B. ODELL, OF RIVERSIDE, CALIFORNIA.

STEAM-GENERATOR HEATING UNIT.

Application filed April 18, 1928. Serial No. 270,908.

This invention relates to electric heating units and more especially to electric steam generator units for apparatus of the kind shown in my Patent #1,662,935, March 20, 5 1928.

An object of my invention is to provide a novel unit whereby to obtain a high heating efficiency for the quick and continuous generation of steam, more especially in domestic 10 steam radiators employing electric energy as the source of heat.

More particularly an object is to provide a heating unit of such construction that heat is transmitted to and absorbed by both upper 15 and lower stretches of coil of tube enclosing resistance coils of the unit.

A further object is to provide a mount for the resistance coils wherein the coils are rove to and fro and are disposed within a wrapping coil of water tube.

Other objects, advantages and features of construction, combination and details of means will be made manifest in the ensuing description of the herewith illustrative embodiment; it being understood that modifications, variations and adaptations may be resorted to within the spirit, scope and principle of the invention as it is more directly claimed hereinafter.

30 Figure 1 is a plan of the installed unit.

Figure 2 is a cross section of the resistance mount.

Figure 3 is a longitudinal edge view of the mount.

35 Figure 4 is a detail view of a terminal spring contact, and

Figure 5 is a detail of its plug blade.

Figure 6 is a central section of a three-way plug socket.

40 Figure 7 is a face view thereof, and

Figure 8 is a sectional view of the three-way plug.

In the above referred to patent a heating unit is adapted to be readily inserted and removed under a steam radiator; the units being placed beneath a set of water conduits which are to be heated to supply steam to the radiator shell.

50 My present invention has for its broad object to provide a highly efficient form of steam generating electric unit, and to provide a plural-section resistance wire wherein the different sections of the resistance wire are parallel connected in a three-way wire electric system.

The unit includes a rectangular frame 2

preferably of a fire-resistive glass of kinds now in common use for cooking utensils. This frame, or mount, is provided with suitable cross-webs 3 shown as having acute upper edges 4 on which rest the cross stretches of resistance-wire coils 5, hereinafter called the heating elements. The coils of these elements lie below the top plane of the frame 2 which has top semicircular recesses 6 forming lugs 7 along inner edges of the frame. The lugs are undercut at 8 to form safe retainers for the bends of the element coils.

60 The rear side of the frame has a set of three terminals or blade plugs 10 and the heating element includes duplex coils A—B starting from the central plug 10 (or neutral line N) and ending at the respective outer plug 10, Fig. 1.

65 The plugs 10 are adapted to be plugged into respective spring clip terminals 12 which have stems 11 secured in the wall W which indicates a portion of a steam radiator apparatus.

70 The neutral line N serves the central plug 10 and wires L—M serve the outer clips 12 so that should either loop or section A—B of the heating element break, the remainder would still be a hot wire.

75 Thus the heating element is fully exposed above and below and its radiant heat is effectively transmitted to an enveloping coil or coils of small water tube 15 wound from end to end over the frame 2. The ends of the tube are connected in any suitable manner to water and steam receivers, not here shown. The frame is quite shallow and thus the tube coils 15 lie close to the hot heating element sections A—B and high efficiency is secured 80 in heating water in the tube 15.

85 In event of necessity the whole electric unit can be readily pulled from its connectors 12 and easily replaced.

90 In Figs. 6, 7 and 8 is shown a three-wire plug socket including a face plate 25 having equiangular plug holes 26 leading into an insulator body 27 in which is mounted three spring clip terminals 28. These have binding stems 29 at the bottom of the insulator for wires. A shell 30 encloses the insulator 95 and has a flange 31 attached to the back of the face-plate 25.

100 Complementary to the socket is a three blade plug having a disc insulator 32 with a set of perpendicular blade plugs 33. These have stems 34 extending through the disc 32 105 and secured by binding nuts 35. The bind-

ing stems 35 are concealed in a protective hood 36.

What is claimed is:

1. In an electric heater a flat frame of refractory material, a flat system of resistor element with its stretches in a common plane crossing from side to side of the frame and between its top and bottom faces, and a water tube consisting of a flattened helix coiled on the frame and in close proximity to opposite sides of the plane resistor system.
2. In an electric steam generating unit, a naked resistor member rove to and fro in a plane to form a flat grid element, means supporting the grid in plane form, and a water tube forming a flat helix about the grid with

its coils in close proximity to opposite sides of the grid-forming member; whereby heat from both sides of the naked member is imparted to the coil.

3. In an electric steam generating unit, a flattened helix of water tube, and a plane grid of naked resistor element disposed and wholly exposed within the helix coils and in close proximity to the convolutions, whereby heat is transmitted from both sides of the element forming the grid to the enveloping helix, and means for supporting the naked grid in position for lateral radiations from both its faces to the helix.
